United States Patent Office

Des. 205,050
Patented June 14, 1966

205,050

COMB

Anton Rizner, Elmhurst, Ill., assignor to H. Fishlove &
Co., Chicago, Ill., a corporation of Illinois

Filed Nov. 9, 1964, Ser. No. 82,534

Term of patent 14 years

(Cl. D86—8)

The side opposite that shown in FIGURE 1 is the same as that shown in FIGURE 1.

I claim:

The ornamental design for a comb, as shown and described.
